REELING DEVICE AND METHOD OF REELING

Fritz Pollak, Jackson Heights, N. Y., assignor to
 Oscar Kohorn & Co. Ltd., New York, N. Y., a
 corporation of New York

Application November 2, 1943, Serial No. 508,697

7 Claims. (Cl. 28—71.6)

My invention relates to a new and improved reeling device, and to a new and improved method of reeling yarns, filaments, threads, and flexible bodies of all shapes and of all materials.

The invention is particularly useful in handling filaments of artificial silk which are produced by forcing a suitable spinning solution, through a spinning nozzle.

While such filaments are wound upon one or more reels, such filaments can be subjected to any suitable operations, such as desulphurizing, bleaching, washing, drying, etc.

According to my invention, a helix of the filament is supported circumferentially upon a rotatable reel, wholly upon supporting members which are connected to said reel, so that said supporting members are rotated in unison about the longitudinal axis of rotation of the reel. Said supporting members are spaced radially from said longitudinal axis of the reel.

Said supporting members are arranged in two or more sets. One of said sets may be fixed relative to the reel. Another set is connected movably to said reel, so that the supporting edges of said relatively movable members are movable radially inwardly and outwardly, relative to said longitudinal axis.

The circumferential configuration of the helix may be circular or polygonal. The major part of the helix preferably always has the circumferential shape of a circle which is concentric with said longitudinal axis, or of a polygon whose centre is on said axis. A minor zone or part of the circumference of the helix is bulged radially outwardly relative to the major part of the circumference of the helix. For convenience, I refer to the circumference of the helix, even if it has a polygonal shape in a plane which is perpendicular to the longitudinal axis of rotation of the helix.

The minor bulged zone of the helix is shifted in a circumferential direction.

Hence, the helix always has the same circumferential shape; but the location of its bulged zone is continuously angularly shifted in a circular path which is in a plane which is perpendicular to the longitudinal axis of the helix.

The bulged zone is intermittently fed forwardly. Hence, the entire helix is fed forwardly, in a series of intermittent forward feeding strokes, each forward feeding stroke operating upon a respective circumferential portion of the helix. Consecutive feeding strokes operate upon different circumferential portions of the helix.

Numerous additional important objects of the

invention are stated in the annexed description and diagrammatic drawing, which illustrate two preferred embodiments thereof. It is to be understood that the above general statement of the invention does not limit its scope.

Fig. 1 is a section, partially in elevation, through a vertical plane which passes through the axis of rotation of the reel.

Fig. 2 is an enlarged partial top plan view of the top movable sleeve of Fig. 1.

Fig. 3 is an end elevation, taken at the front or right-hand end of Fig. 1.

Fig. 4 is a partial view, similar to Fig. 3, of a second embodiment.

The embodiment of Figs. 1-3 will first be described.

Fig. 1 shows a reel 2, which is turnably mounted on shaft 1, so that reel 2 and shaft 1 can be freely rotated relative to each other.

Shaft 1 is rotated about its longitudinal axis by any suitable means. Reel 2 is rotated about the longitudinal axis of shaft 1, and relative to shaft 1, by means of gear 11 which is fixed to said reel 2.

A face cam 10 is fixed to shaft 1. The profile of the front operative face of said cam 10, is indicated by the line 10a. The front operative face of said cam 10, which is the right-hand face in Fig. 1, is of annular shape. Said front operative face of said cam 10 corresponds to the intersection with a cylindrical annulus which has a horizontal axis, of a plane which is co-incident with line 10a. Said front face of cam 10 can be of any contour, and said front face may have a sharply defined step, instead of having edges which have a general uniform elliptical contour.

A set or series of tubes 4 are fixed to reel 2. Each tube 4 has a longitudinal axis which is parallel to the common longitudinal axis of rotation of shaft 1 and reel 2. These tubes 4 are identical, and their angular spacing is equal. In the embodiment of Fig. 3, there are twelve tubes 4, but this number can be varied.

A respective sleeve-carrier 5 is both slidably and turnably mounted on each tube 4. Each sleeve-carrier 5 has a tapered or wedge-shaped projection 6a fixed thereto. Each tapered or wedge-shaped projection 6a has a thread-supporting surface or edge 6. Each edge 6 may be sharp or blunt and it may be of any shape, such as a rounded shape, etc.

Each sleeve-carrier 5 has a rear flange 9, which is held in contact with the front operative face of cam 10. Each sleeve-carrier 5 is biased so that its flange 9 slidably contacts with the front

operative face of cam 10, by means of a biasing compression spring 12. For this purpose, a longitudinal rod 5a is fixed to the front end-wall 5c of each sleeve-carrier 5. Each rod 5a is located in a respective tube 4. Each spring 12 has its front end abutting a respective plug 12a, which is fixed to the respective tube 4. Each rod 5a has a head 5b fixed thereto. Each head 5b is located rearwardly of the respective plug 12a. The rear end of each compression spring 12 abuts 10 the respective head 5b.

A second series of bars or carriers 3 are fixed to the reel 2. Each said bar or carrier 3 has a tapered projection, which has a thread-supporting surface or edge 7. Said edge 7 may be 15 sharp or blunt, rounded, etc. The edges 7 are of sufficient length to support all the turns of the helix of the thread 14.

Fig. 2 shows that the wall of each sleeve-carrier 5 has a slot or groove 13a which is of general triangular shape between its front and rear corners. This groove 13a has a leg L, whose shape is substantially that of a part of a helix. This groove 13a has another leg La, which has two branches, each branch having the shape of 20 a part of a helix. The branches of leg La are inclined to each other. The rear branch is more sharply inclined than the front branch, relative to the longitudinal axis of sleeve 5.

Each tube 4 has a guide pin G, which projects 30 into the respective groove 13a of the respective sleeve-carrier 5. Hence, when a sleeve-carrier 5 is in its extreme rearward position, the respective pin G is at the front corner of the respective groove 13a.

During each longitudinal forward movement of a sleeve-carrier 5, the respective pin G which is fixed to the respective tube 4, is located in the leg L, so that the turning effect on each sleeve-carrier 5 during said forward movement, is the same as though pin G were moved rearwardly in leg L. Hence, during each longitudinal forward stroke of each sleeve-carrier 5, said sleeve-carrier is uniformly turned clockwise, if the observer is standing in front of the reel 2, namely, at the right of reel 2 in Fig. 1.

During each rearward stroke of a sleeve-carrier 5, said sleeve-carrier 5 is first turned sharply counterclockwise, so that the respective edge 6 will promptly lose contact with the respective part of the helix of the thread 14.

As an example, during each forward stroke of a sleeve-carrier 5, its edge 6 can engage the helix of the thread 14 and raise the entire respective part of the helix radially outwardly from the adjacent edges 7, while the reel 2 is turned through an angle of thirty degrees to forty-five degrees, and even thirty degrees to ninety degrees. The operative thread-raising positions of edges 6 are shown in positions F, E, C, A. In said positions, the respective bulged part of the helix is supported only on the respective four edges 6. In position A, the sleeve-carrier 5 is at the end of its forward stroke. In position B, the sleeve-carrier 5 is at the end of its rearward stroke. During its rearward stroke, each edge 6 loses contact with the helix, while the reel is turned through a small angle of about fifteen degrees, as shown in position D.

Each edge 7 is of sufficient length to contact 70 with all the turns of the helix of the thread 14 which is wound on the reel.

Assume that only the edges 6 support the helix of the thread 14, raised radially outwardly from edges 7, in an arc of forty-five degrees anterior

to the position A. The helix of the thread 14 will be supported on the edges 7, in the remaining part of the circumference of the helix. The part of the circumference of the helix, in which the turns of the helix of thread 14 are supported wholly on edges 6, is called the bulged part or zone or said helix. As later described, said bulged part is continuously shifted clockwise around the circumference of the reel, if the observer is in front of the reel.

Hence the bulged part of the helix is sometimes at its top, sometimes at its bottom, etc.

It is preferred simultaneously to rotate cam 10 and reel 2 in the same direction, but at different angular velocities. As an example, the reel 2 can turn sixty revolutions per minute, and the cam 10 can turn in the same clockwise direction, seventy-two revolutions per minute. The length of each forward feeding movement of the respective bulged part of the helix of thread 14, may be 0.09 inch. The thread 14 is always wound or supported continuously upon some of the edges 7 and on some of the edges 6, and it is unwound continuously at the front end of the reel.

In the embodiment of Fig. 4, the only difference is that each sleeve-carrier 5 is located circumferentially between a pair of bars 3.

In the construction shown, the front ends of bars 3 and of the supporting edges 6 of sleeve-carriers 5, are free from any obstruction. Hence the front turn or turns of the helix can be fed intermittently over the free front end of the reel. The thread which is thus unwound from the front end of the helix can fall into a suitable receptacle, or it can be wound upon a reeling device. The thread which depends from the helix at its front end, can therefore be free from tension, or it can be subjected to continuous or intermittent tension.

In the embodiments described herein, the number of edges 6 is equal to the number of edges 7. The invention is not limited to this relation.

In order further to illustrate the invention, if the helix is made of artificial silk filament 14 which is supplied by a spinning nozzle, the thickness of said filament 14 is about 300 denier or more. There will be seventy-six turns of such filament 14 in the helix. The longitudinal distance between adjacent turns will be 0.09 inch. The longitudinal stroke of sleeve-carriers 5, from maximum rearward position to maximum forward position will be .09 inch. The normal diameter of the helix, as determined by edges 7, will be six inches. The maximum radial enlargement of the helix will be 0.125 inch, in the bulged part of the helix.

Whenever reference is made to a thread in a claim, this designation includes filaments and flexible members of all shapes and of all materials.

By increasing the number of bars 3, the transverse contour of the thread of the helix can be made to approximate a circle.

The invention is not limited to the use of bars or carriers 3, which are fixed to reel 4.

The shape of the helix is invariable, even though the position of its bulged zone or part is shifted circumferentially around the reel.

The filament or thread which is led off the helix, is preferably subjected to continuous and uniform tension. Hence, the filament or thread can be subjected to uniform tension at all times.

I have described preferred embodiments of our invention, but numerous changes and omis-

sions and additions can be made without departing from its scope.

For convenience, the radial direction may be designated as the transverse direction, and the circumferential spacing of members 3 and 5 may be designated as lateral spacing.

Since the cam and the reel are rotated at different angular speeds, the high point of the cam, which controls the extreme forward position of each movable sleeve-carrier 5, is shifted circumferentially relative to the reel.

Hence, the automatic means which operate the reel and the cam, progressively shift the location of the movable sleeve-carrier 5 which is in its extreme forward longitudinal position.

Hence, the location of the portion of the helix which is fed longitudinally forwardly, is progressively circumferentially shifted. The angle of the circumferential shift between successive movable sleeve-carriers 5, is less than the angle of the portion of the helix which is forwardly longitudinally fed.

The entire helix is at all times located on supporting means which move in unison with the reel, around the axis of rotation of the reel. There is little or no circumferential shift or rubbing movement between the helix and its supporting means.

When I refer to a helix, I include a winding whose respective turns may be of different shape and of different dimensions.

I claim:

1. A method of handling a thread or the like, which consists in maintaining a length of said thread in the form of a helix, rotating said helix about a predetermined longitudinal axis, maintaining only a portion of said helix radially outwardly bulged relative to the remainder of said helix, shifting said bulged portion circumferentially around the helix while maintaining said helix in fixed shape, and longitudinally forwardly feeding only said bulged part of said helix.

2. A method of handling a thread or the like, which consists in maintaining a length of said thread in the form of a helix, rotating said helix about a predetermined longitudinal axis, maintaining only a portion of said helix radially outwardly bulged relative to the remainder of said helix, shifting said bulged portion circumferentially around the helix while maintaining said helix in fixed shape, and longitudinally forwardly feeding only said bulged part of said helix, said bulged portion of said helix occupying only a minor part of the circumference of the helix.

3. A method according to claim 1, in which the thread of the helix is maintained under substantially constant tension.

4. A method of handling a thread or the like,

which consists in maintaining a length of said thread in the form of a helix, wholly and continuously on a support which is rotatable about a longitudinal axis, moving said helix longitudinally on said support without substantially moving said helix circumferentially relative to said support, said helix being thus moved longitudinally, only in a circumferential zone of said helix which is shifted circumferentially around said helix.

5. A mechanism comprising a reel which is mounted to rotate about a longitudinal axis, longitudinal thread-supporting means connected to said reel and movable in unison with said reel around said axis, said thread-supporting means being adapted to support a helix of thread or the like, said thread-supporting means being transversely spaced from said axis, said thread-supporting means including a plurality of laterally spaced movable members, each said movable member being turnable back-and-forth around its respective longitudinal axis relative to the reel, each said movable member being also movable longitudinally to-and-fro relative to said reel, each said movable member having a thread-supporting wall, each said movable member being turnable relative to the reel to an operative position in which its wall abuts and supports the respective adjacent part of the helix, each said movable member being turnable relative to the reel to an inoperative position in which its wall is spaced from the respective part of the helix, automatic operating means adapted to rotate the reel and to move said movable members relative to the reel in the aforesaid respective directions, said operating means moving each movable member to said operative position during its forward longitudinal movement thereof, and moving each movable member to said inoperative position during each backward longitudinal movement thereof, each movable member moving the respective adjacent part of the helix longitudinally forwardly during each to-and-fro movement of said movable member.
6. A mechanism according to claim 5, in which said automatic actuating means include a cam which progressively shifts the location of the movable member which is in its extreme forward longitudinal position.
7. A mechanism according to claim 5, in which said automatic operating means include a cam which is rotated around said longitudinal axis in unison with said cam, the angular speed of rotation of said cam being different from the angular speed of rotation of said reel so as to circumferentially shift the cam and reel relative to each other, said cam operating said movable members longitudinally.

FRITZ POLLAK.
